ROTATABLE INDEX DISK

Lawrence C. Hill, Boston, Mass.

Filed May 12, 1964, Ser. No. 79,947

Term of patent 14 years

(Cl. D52—1)

FIG. 1

FIG. 2

FIG. 1 is a plan view of a rotatable index disk showing my new design, and

FIG. 2 is a rear view of the disk.

The disk comprises sectors lined to indicate different colors and each includes a wedge-shaped area lined to indicate transparency. The disk is of the thickness of heavy cardboard.

I claim:

The ornamental design for a rotatable index disk, substantially as shown and described.
